UNITED STATES PATENT OFFICE

KENNETH W. MILLER, OF CHICAGO, ILLINOIS

CABLE TOOL

Application filed March 20, 1926. Serial No. 96,176.

This invention relates generally to tools for removing the metal sheath from insulated, metal-covered cables or the like.

Metal sheathed cables are used for submarine and subterranean transmission lines. In joining or splicing the cable requires the removal of part of the sheath from the ends to be joined is required.

Heretofore this has been effected by the use of a knife generally driven into the sheath by means of a hammer. In the hands of an unskillful or careless operator, this often results in damage to the insulation of the cable.

An object of this invention, is to produce a simple, rugged, inexpensive tool, with which a workman can without special skill quickly and neatly sever the metal sheath surrounding such conductors without injury to the underlying insulation.

Several advantageous features of the preferred form of this invention are as follows:

It is adjustable with respect to the diameter of the cable. It is also adjustable as to the varying thicknesses of the sheath. Spring means is incorporated in the present invention to enable the cutter to cut a groove of uniform depth in the sheath regardless of the deformities of variations in the surface of such sheath and regardless of the cable being somewhat "out of round." The tool can be operated on cable with a very small clearance between it and adjacent cables or between the wall and other obstructions.

Other objects and advantages, as well as a plurality of modifications, will appear more fully in the following detailed description which is supplemented by the accompanying drawings, in which like reference numerals indicate identical parts throughout, and in which

Fig. 1 is an elevation of the novel sheath cutting tool;

Fig. 2 is a plan view of the same;

Fig. 3 is an enlarged longitudinal section through the cutter and novel adjusting means associated therewith as seen on the line 3-3 of Fig. 1, looking in the direction indicated by the arrows;

Fig. 4 is an end view of the same showing means for retaining the cutter in desired adjustment.

Fig. 5 is the other end view of the cutter assembly showing adjustment pin and calibration feature,

Fig. 6 is a detail of the eccentric shaft in the plane of its eccentricity.

Fig. 7 is a sectional view of a part of the invention, showing in detail several of its features as seen on the line 7-7 of Fig. 2 looking in the direction indicated by the arrows.

Fig. 8 is an enlarged detail of my preferred form of track roller.

Fig. 9 is a longitudinal section of the sheath showing the nature of the cut made by the tool.

Fig. 10 is an enlarged detail of a roller which may be substituted for the preferred form of roller shown in Fig. 8.

Fig. 11 is a longitudinal section of a modification of the invention;

Fig. 12 is a detailed, transverse section of a part of the modification shown in Fig. 11, as seen on the line 12-12 of Fig. 11 looking in the direction indicated by the arrows.

Fig. 13 is a detail of the special bifurcated plunger used in this modification.

Fig. 14 is a detail of a stop or retainer used to hold the plunger in its socket.

Fig. 15 is a detail of a somewhat similar stop which holds the entire cutter assembly and the pressure screw against axial movement with respect to each other; and

Fig. 16 is a detail of the pressure screw.

In the accompanying drawings, Figs. 1 to 10 inclusive depict a preferred form of my invention. 20 denotes generally a framework composed of a pair of arcuate-shaped steel plates 21 and 22 which are geometrically symmetrical with respect to each other, and have a set of diametrically opposed ears 23 and 24 which, with cast aluminum blocks 25 and 26 (Fig. 2) fastened between them by rivets as at 27 form handles for the manipulation of the tool. A steel block or spring chamber 28 is mounted between the plates 21 and 22 and is fastened in place by rivets as at 29. These three blocks also serve to rigidly main-

95

100

tain the two plates 21 and 22 in fixed parallel relation to each other.

5 Rotatably mounted upon the bolts 30 and 31 which are carried by the frame 20 and held therein by nuts 32 and 33 respectively are two rollers 34 and 35.

10 Pivottally mounted between the frame plates 21 and 22, upon a machine screw 36 onto which is screwed a nut 37, and spaced from each other by sleeve 38, are two steel arms or levers 39 and 40 which are also geometrically symmetrical with respect to each other. These arms are rigidly maintained in fixed parallel relation to each other by the 15 frame plates 21 and 22 the collar 38, the bolt 36 and nut 37, and also by a pin 41 which has shoulders formed thereon upon which the inside surface of the plates 39 and 40 rest. The pin 41 has smaller end sections 42 which 20 are forced tightly into the arms 39 and 40 but do not extend beyond the outermost faces thereof, in order that the pivotal movement of these arms will not be impaired by the ends of the pin 41 contacting the plates 21 and 22. Correct spacing and rigidity of 25 arms 39 and 40 is further maintained by the cutter shaft 51 and member 45 which are described later. Thus, these arms really form one, pivoted rigid lever.

30 A pair of pins 43 and 44 of a construction similar to 41, with the exception that the end sections run through the plates 21 and 22 and are peened over serve to further rigidify the framework 20. A similar set of pins may 35 easily be substituted for the aluminum blocks in order to cheapen the construction if so desired.

40 Rotatably carried between the arms or levers 39 and 40 at the short end thereof, and at a comparatively short distance from the pivot bolt 36, is a cross member 45 having suitable bearing lugs 46 and 47 journaled in the arms 39 and 40 respectively, but not extending beyond their outer surfaces. A 45 threaded winged screw 48 is run through the midpoint of the member 45 at right angles to its axis of rotation. One end of the screw has a flat wing 49 for enabling it to be easily turned by the fingers. The other end of this 50 threaded screw 48 has a smooth rounded portion, as shown at 50.

55 The novel, adjustable cutter mechanism, best shown in Figs. 3 to 6 inclusive is mounted at the remaining ends of the pivoted levers 39 and 40 at a distance relatively greater from the pivot bolt 36 than the member 45. The main bearing shaft 51 extends through and is journaled in the plates 39 and 40 at bores 52 and 53 respectively.

60 The shaft 51 is machined to three successively decreasing diameters 54, 55 and 56. The bore 53 serves as a bearing for the section 54 of the shaft, and bore 52 serves as a bearing for section 56 of the shaft. Sections 54 and 56 of the shaft in turn serve

as bearings for the rollers 57 and 58, which limit the depth of the cut. Section 55 of the shaft 51 is eccentric with respect to the axis and acts as a bearing for the cutter wheel or disk 59 which is of a construction well known in the art. The end of the shaft 70

protruding past the outside face of the arm plate 40 is of squared transverse section and forms a projection 60. As shown in Figures 2 and 4, a suitably formed clip 61 is 75 pivoted to the arm plate 40 by a rivet 62. This clip has a surface 63 of such a shape as to fit against the square section 60 of the shaft 51 to thus hold it against rotation. The end of the clip 61 extends past the end 80 of the arm 40 far enough to render it easily swung free of the end of the shaft 51 angularly out of effective position. A cotter pin 64 is placed through a hole in section 56 of the shaft 51 at a location such that it will 85 prevent axial movement of the shaft. This pin also acts as a handle to turn the shaft to any desired setting, as shown in Fig. 5. An arrow 65 is stamped on the end of the eccentric shaft 51 and numbers on the face 90

of the arm plate 39 indicating in 64ths of an inch, the depth of cut obtained by any of the four settings. The amount of eccentricity of section 55 of the shaft, the relative diameters of the cutter disk 59 and rolls 58 and 57, and the angle at which the surface 63 on the clip 61 is formed, are all so chosen that the depth of cut will vary in 4 equal and definite steps. It may therefore be seen 95

that the eccentric arrangement of the section 55 together with the arrangement whereby the shaft 51 may be locked in any one of a number of different radial positions constitute means for adjusting the cutter 59 transversely of the rolls 57-58. The location of the rollers 34 and 35 and pivot bolt 36 is so chosen in relation to the length of the cutter arm between the point 36 and the shaft 51 that the same side of the eccentric portion 55 of the shaft 51 is always presented to the 100 cable regardless of the cable diameter, provided, of course, that the shaft 51 itself remain locked against rotation. In this manner the calibration of the tool is simple and definite. 110

115 Referring now to Fig. 7 the end 50 of the aforementioned screw 48, engages the depressed face 67 of the plunger 68, which is free to move axially within the bore 69 in the block 28. The bore 69 is constricted as at 70 so as to confine the plunger 68 therein. A spring 71 of slightly smaller diameter than the diameter of bore 69, fits about a projection 72 on the plunger 68, and also about a similar boss 73 on a threaded plug 74 which is fitted into a threaded portion 75 in the other end of the bore, and can be turned by means of a slot 76. The spring 71 is of the compression type, assembled with sufficient initial compression and powerful enough to 120

urge the cutting wheel 59 into the sheath provided the pressure screw 48 is turned down a small amount after the tracking rolls 34 and 35 and the cutter disk 59 are all making contact with the cable sheath.

In order to maintain at all times the end 50 of the screw 48 in contact with the depressed face 67 of the plunger 68, a horseshoe spring 77 is mounted around the collar or sleeve 38. One end of the spring 77 engages the pin 41 previously described. The remaining end engages the pin 44. This horseshoe spring is assembled under sufficient tension to urge the lever assembly in a counter clockwise direction and thus keep the socket and end of the pressure screw in engagement at all times.

Now it is well known to those familiar with the art that when a cutting wheel of the type shown at 59 is employed, the metal being cut is raised up or crowded into ridges 78 (Fig. 9) immediately adjacent to both sides of the cut. Hence, the rollers 34 and 35 have been relieved centrally as at 79 (Fig. 8) in order to permit the surface of the rollers to ride upon the surface of the element to be cut without rolling down the ridge or burr and thus forcing the sheath down into the insulation.

In order to provide a tool still easier of manipulation there have been devised special guiding rollers as shown in detail in Fig. 10. These rollers have a guiding ridge 80 which falls into the groove started by the cutter and, as the guiding ridges of both rollers and the edge of the cutter are substantially within one plane, and their axes are held substantially at right angles to the peripheral surface of the element to be cut by the faces of the rollers, as well as the rigid plates 21, 22, 39 and 40, the cutter must consequently follow a transverse path. These guiding rollers are relieved on opposite sides of the guiding ridge 80 to bridge over the ridges or burrs 78 formed immediately adjacent to both sides of the cut, as shown at 791. Thus the tool is self guiding and an inexperienced and unskillful operator can effect a neat cut with facility.

It is also well known that, although lead sheathed cables may be manufactured so as to have a perfectly circular transverse section, they do not remain so. Due to their being coiled, handled, etc., they become to some extent deformed. It can be readily seen how a rigidly mounted cutter would cut a groove of varying depth, depending upon the extent of the deformation of the conductor. Also, as various sizes of the conductor have sheaths of different thicknesses, it would be very convenient to have a cutter which is positively limited to cut to a predetermined depth, and some manner of adjusting the same.

In order to limit the depth of the cut, a pair of rollers have been provided disposed

adjacent to both sides of the cutter and the manner in which they will ride upon the surface is believed to be perfectly apparent. The feature of adjustability has been accomplished by having the cutter journalled upon an offset or eccentric bearing or crank. Upon turning the shaft 51 by means of the pin 64 the depth of the cut can be controlled at will and fixed by slipping the clip 61 against the square end 60 of the shaft 51.

Now as the pressure exerted by the cutter 59 upon the surface of the cable really depends upon the spring 71 then when this spring tension is ample, it is obvious that the disk will cut deeper and deeper into the sheath as the tool is revolved, but only as deep as the rollers 57 and 58 will permit. Then, these rollers ride upon the surface, taking in all its irregularities, the spring 71 permitting of this action.

Attention is directed to the fact that the lever like construction of the arm 40, carrying the cutting element, causes the cutting element to be movable through a greater distance than that through which the screw 48 which exerts the force must move. Of course, the force exerted by the cutter element is proportionately decreased.

The lever arms 39 and 40 provide, by means of the different distances of the cutting wheel 59 and the screw from the pivot, means whereby a wide range of cable sizes can be handled by a small amount of adjustment of the screw. Thus the screw may be made much shorter than ordinarily and the tool is made far more compact than would otherwise be possible. Also this construction permits of the short handles which for any cable size do not exceed a working radius in excess of six inches from the center of the cable.

In order to further lessen the time required for its manipulation, there is provided a trip release for the screw. That is to say, means are provided whereby the operator does not have to release the arm 39 and 40 by turning the screw 48 all the way in order to set the tool about the conductor and then turn it back to bring the cutter into engagement with the surface. This operation can be performed by pushing inwardly upon the lever or by pulling the turning screw upward and inward so as to permit the end 50 of screw 48 to be disengaged from the socket 67. The screw can then be swung to the position shown in dotted lines in Fig. 1 passing over a rounded notch 81 in the spring chamber block 28 provided for this purpose, and thus all that is necessary to render the tool ready for cutting is to place the tool about the cable, replace the screw 48, and turn it a slight amount.

In a tool of this kind, rugged and inexpensive construction is particularly desirable. The great rigidity of the framework has already been disclosed and the simplicity

of the construction is apparent. The plates 21, 22 and 39 and 40 may be stamped and then placed by pairs in a jig and drilled together. This insures cheap and very accurate construction. The remaining parts are inexpensive to make and are all easy of construction and of common materials.

The cutter disk and roller assembly can easily be dismantled for repair or replacement by removing cotter pin 64, afterward revolving clip 61 on its pivot 62 so that it clears the shaft end 60 and portion 54 of largest diameter. The shaft will then slide freely towards the larger diameter section 15 or toward the left in Fig. 3. This is made possible by choosing the diameters 54, 55 and 56 so that neither 55 nor 56 are too large to pass through the bore 53 in the arm 40, or through the bores of the roller and cutter 20 disk to their left.

The spring chamber can be easily opened and parts removed for cleaning or repair by unscrewing the slotted plug 74.

Figs. 11 to 15 inclusive disclose a modification of the invention in which the pivoted arms are not used. A cast frame 20' is provided of a construction similar to that used in some styles of pipe cutters. This frame is cored and machined at 82 and 63 to receive 30 guiding rollers 34' and 35' which are identical in construction to those shown in the other modification as 34 and 35. These guiding rollers are mounted on bolts 30' and 31' which are held in the frame by nuts in exactly the same manner as 30, 31, 32 and 33 shown in Figs. 1, 2, 7 and 8.

The T-shaped flange 83 is passed along the inner straight portion of the casting 20' and is machined to act as a guiding strip 40 along which block 28' may slide. The cast iron block 28' is slidably mounted on the flange 83 and is properly slotted at 87 to preserve alignment. The remaining end of frame 20' is threaded at 88 to receive the operating screw 48'. The cast iron block 28' has a longitudinal rectangular slot 69' at its upper portion into which is slidably mounted a plunger member 68'. This plunger member is bifurcated and drilled at one end to receive an eccentric cutter assembly of construction identical with that shown in Figs. 1 to 5 inclusive, and before described. The other end is bored out to receive and house a compression spring 71'.

The plunger member 68' is prevented from over travel in the direction of the cable by a small plate 89 which is screwed to the cast block 28' by screws 90. A lip 91 extends a small distance between the slotted faces of member 68' and prevents it from moving too far out. A slotted plate 92 is screwed onto the other end of the cast block 28' by screws 93. It provides a bearing face for one end of the spring 71' and the slotted portion 94 receives an annular groove 95 cut in the end

of the screw 48'. The screw 48' may be revolved by a handle 49' to cause cast block 28' to slide along to the flange 83 of the main cast frame 20'. The inner end 50' of the screw 48' has the further purpose of acting as a central guide to one end of the spring 71'.

The movement of the plunger 68' is intended to take care of the irregularities of the sheath and has only a small travel.

In applying the tool to the cable after the cutter disk has made contact with the sheath the screw should be turned just enough to force the plunger member into the midposition of its possible travel. Spring 71' is of sufficient stiffness and is assembled under a sufficient initial tension to force the cutter disk into the cable. In this modification of the tool by the use of cast parts some gain is made in construction simplicity and 85 rigidity. However, it does not have the trip release and the length of the handle is necessarily longer, so that the tool cannot be used with such limited clearances as shown in Fig. 1.

It is to be understood that the use and construction of this invention is not limited to the above disclosure except only in so far as defined by the scope of the appended claims.

I claim:

1. In a tool for forming a groove of a predetermined depth in the peripheral surface of an element of substantially circular transverse section, a cutting element, means for urging said element into said surface, said surface and said element being relatively movable to form said groove, limiting means associated with said cutting element for positively limiting the extent to which said urging means may cause it to enter said surface, resilient means associated with said urging means for enabling said urging means to compel said cutting element and said limiting means to follow all convolutions of said surface and a second resilient means for maintaining said first resilient means and said urging means in positive engagement.

2. In a tool for forming a groove of predetermined depth in the peripheral surface of an element of substantially circular transverse section, a cutting element, means for urging said element into said surface, said element and said surface being relatively movable to form the groove, limiting means associated with said cutting element for limiting the extent to which said urging means may cause it to enter said surface, resilient means for enabling said urging means to compel said cutting element and said limiting means to follow all convolutions of said surface, a second resilient means for maintaining said first resilient means in positive engagement with said urging means, and release means for quickly causing said urging means and said first resilient

90

130

means to become ineffective and permitting said second resilient means to urge said cutting element away from said surface.

3. In a tool for forming a groove of a predetermined depth in the peripheral surface of an element of substantially circular transverse section, a cutting element, means for urging said element into said surface, said element and said surface being relatively movable to form said groove, means associated with said element and said urging means for transmitting the force and movement of said urging means to said cutting element and causing said cutting element to be moved to a greater distance than that through which said urging means exerts its force, means associated with said cutting element for limiting the extent to which said urging means may force it into said surface, 20 resilient means for enabling said urging means to compel said cutting means and said limiting means to follow all convolutions of such surface, a second resilient means for urging said first resilient means and said urging means into positive engagement, and release means for quickly causing said urging means and said first resilient means to become ineffective and permitting said second resilient means to move said cutting element away from said surface.

4. In a tool of the character described, a frame adapted to be positioned about a cable or similar article, a supporting structure mounted on the frame and adjustable toward and away from the cable receiving portion thereof, a cutter, limiting rolls adjacent the cutter, a common support for the cutter and rolls carried by the supporting frame, and means for adjusting the cutter transversely of the rolls.

5. In a tool of the character described, a frame adapted to be positioned about a cable or similar article, a supporting structure mounted on the frame and adjustable toward and away from the cable receiving portion thereof, a shaft mounted in the supporting structure, a cutter carried by the shaft, limiting rolls mounted on the shaft adjacent the cutter, and means for adjusting the cutter transversely of the rolls.

6. In a tool of the character described, a frame adapted to be positioned about a cable or similar article, a supporting structure mounted on the frame and adjustable toward and away from the cable receiving portion thereof, a shaft mounted in the supporting structure and having an eccentric portion, a rotary cutter mounted on the eccentric portion of the shaft, limiting rolls mounted on the shaft in coaxial relation and disposed adjacent the cutter and means for adjusting the shaft about its axis.

7. In a portable hand tool for forming a groove in the peripheral surface of an element of substantially circular transverse sec-

tion, a frame within which the element is mounted and against which the element bears, a lever including a shorter and a longer arm pivoted thereto, a cutting element associated with said longer arm, means associated with said shorter arm for urging said cutting element into said surface, said surface and said cutting element being relatively movable to form the groove.

8. In a portable hand tool for forming a groove of a predetermined depth in the peripheral surface of an element of substantially circular transverse section, a frame, a lever including a longer and a shorter arm pivoted thereto, a cutting element associated with said longer arm, means mounted on the frame and associated with said shorter arm for urging said cutting element into said surface, said surface and said cutting element being relatively movable to form the groove, and means for limiting the extent to which the said urging means may cause said cutting element to enter said surface.

9. In a tool for forming a groove of a predetermined depth in the peripheral surface of an element of substantially circular transverse section, a frame, a lever including a longer and a shorter arm pivoted thereto, a cutting element associated with said longer arm, means mounted on the frame and associated with said shorter arm for urging said cutting element into said surface, said cutting element and said surface being relatively movable to form the groove, means for limiting the extent to which said urging means can urge said cutting element into said surface, and resilient means for enabling said urging means to compel said cutting element and said limiting means to follow all convolutions of said surface.

10. In a tool for forming a groove of a predetermined depth in the peripheral surface of an element of substantially circular transverse section, a frame, a lever including a longer and a shorter arm pivoted therein, a cutting element associated with said longer arm, means associated with said shorter arm for urging said cutting element into said surface, said cutting element and said surface being relatively movable to form the groove, means for limiting the extent to which said urging means can urge said cutting element into said surface, a first resilient means for enabling said urging means to compel said cutting element and said limiting means to follow all convolutions of said surface, and a second resilient means for urging said first resilient means and said urging means into engagement.

11. In a tool for forming a groove of a predetermined depth in the peripheral surface of an element of substantially circular transverse section, a lever including a longer and a shorter arm, a cutting element associated with said longer arm, means associated

with said shorter arm for urging said cutting element into said surface, said cutting element and said surface being relatively movable to form the groove, means for limiting the extent to which said urging means can cause said cutting element to enter said surface, a first resilient element for enabling said urging means to compel said cutting element and said limiting means to follow all convolutions of said surface, a second resilient element for urging the first resilient element into positive engagement with said urging means, and a pivotal connection between said urging means and said lever for enabling the said urging means to be moved angularly to become disengaged from said first resilient element to render said urging means and the first resilient elements ineffective, and to permit said second resilient element to pivot said lever so as to urge said cutting element out of and away from said surface.

12. In a cutting mechanism for forming a groove of a predetermined depth in a surface, a shaft including an eccentric portion, a support for rotatably carrying said shaft, a cutting wheel journaled upon said eccentric portion, means for urging said cutting wheel into said surface, said surface and said cutting element being relatively movable to form the groove, a plurality of revolvable elements journaled upon said shaft adjacent said eccentric portion adapted to ride upon said surface and limit the extent to which said urging means may cause said cutting wheel to enter said surface, means for rotating said shaft to cause said cutting wheel to be protruded beyond said rollers into said surface to a greater or a lesser extent to control the depth of said groove, and means whereby said shaft may be locked against rotation.

13. In a tool for forming a groove in the peripheral surface of an element of substantially circular transverse section, a cutting element, means for urging said cutting element into said surface, said cutting element and said surface being relatively movable to form the groove, and a plurality of revolvably mounted roller elements each including a centrally located following ridge adapted to ride in said groove so being formed to guide said cutting element and a plurality of cylindrical surfaces adjacent said guiding ridge adapted to ride on said surface to hold said tool about said surface and having transverse grooves placed adjacent said ridge to bridge over the ridges formed on the surface of said element adjacent said groove in order to permit said cylindrical surfaces of said roller element to contact the surface of said element.

14. In a tool of the character described, a shaft including a plurality of sections increasing in diameter throughout its length,

one being eccentric, a cutting wheel journaled on said eccentric section, means for rotatably supporting said shaft, means for preventing axial movement of said shaft with respect to said supporting means, means for rotating said shaft, and means whereby said shaft may be locked against rotation. 70

15. In a tool of the character described, the combination with a rotatable cutting wheel, the axis of the cutter being parallel to the axis of the work, means for limiting the depth to which it may cut, means for varying the relative position of said cutting wheel and said limiting means to vary the depth to which said wheel may cut, means for fixing said relative position to fix said depth, and means for indicating in advance the maximum depth to which said wheel has been set to cut. 75

16. In a tool for forming a groove in the peripheral surface of an element of substantially circular transverse section, a cutting element, means for constantly urging said element into said surface, means for causing said cutting element to be moved through a substantially greater distance than that through which said urging means exerts its force and with proportionally less force, said tool and said surface being relatively movable to form the groove. 80

17. A hand tool wherein a substantially circular object is gripped between three or more rollers mounted on a frame, at least one of the rollers constituting a cutting tool, and wherein a groove is cut into the object by imparting a relative rotation between the frame and the object, characterized in this—that the non-cutting rollers are provided with grooves in the plane of the cutting edge of the cutting roller, and at least one of the non-cutting rollers is provided with a guiding ridge which rides in the cut groove, said ridge being located centrally of the groove in said last mentioned non-cutting roller. 85

18. In a hand tool adapted to grip a stationary substantially circular surface for cutting a groove therein, a frame including gripping means whereby the frame may be rotated, a circular cutting element mounted on the frame, and a circular roller for limiting the extent of the cutting action, the cutting element and the roller being relatively adjustable for adjusting the maximum cutting distance of the tool. 110

In witness whereof, I hereunto subscribe my name this 8th day of March, 1926. 115
